[57] ABSTRACT

The die assembly is clamped to a die shoe by a locking arm which, when released, permits the assembly to be inserted into and removed from the shoe in a horizontal direction in order to avoid the vertical obstruction presented by a stripper overhanging the shoe. The arm is clamped and released by a vertically reciprocable rod carrying a pin which rides in an inclined slot in the arm to convert the vertical force exerted by the rod into a horizontally directed clamping force of relatively large magnitude.

FIG. 3

PUNCH PRESS WITH ASSEMBLY LOCKING MECHANISM

BACKGROUND OF THE INVENTION

This invention relates to a punch press and, more particularly, to a punch press with mechanism for locking a removable die assembly securely in a die shoe while a vertically reciprocable punch performs a punching operation on a workpiece located between the punch and the underlying die assembly. The latter usually comprises a die fitted removably in a die adapter which, in turn, is telescoped removably into and accurately positioned by a recessed locating seat in the die shoe. In the present press, a stripper is positioned in a stripper housing just above the upper surface of the die to hold the workpiece on the upstroke of the punch and thus strip the workpiece off of the punch as the latter is retracted.

SUMMARY OF THE INVENTION

The general aim of the present invention is to provide a punch press with a novel die assembly locking mechanism which coacts with a uniquely constructed die shoe to lock the die assembly securely in the shoe while permitting the assembly to be quickly and easily inserted into and removed from the shoe in a horizontal direction without obstruction from the overlying stripper housing.

A more detailed object is to achieve the foregoing through the provision of a locking mechanism with a locking arm which, when released from the die assembly, is located below a radially extending slot in the die shoe so as to permit horizontal movement of the assembly through the slot and into or out of the shoe.

Further objects of the invention are to provide comparatively simple, compact and durable actuating means for clamping and releasing the locking arm and also to use the arm for effectively clamping the die to the die adapter while simultaneously clamping the adapter to the die shoe.

The invention also resides in the novel construction of the die shoe to securely seat and accurately locate the die assembly around its entire periphery and yet, at the same time, to enable removal of the assembly without need of moving the stripper housing.

These and other objects and advantages of the invention will become more apparent from the following detailed description when taken in conjunction with the accompanying drawings.

BRIEF DESCRIPTION OF THE DRAWINGS

FIG. 1 is a fragmentary elevational view of a punch press embodying the novel features of the present invention, parts being broken away and shown in section.

FIG. 2 is a fragmentary view similar to FIG. 1 but showing certain parts in moved positions.

FIG. 3 is a fragmentary plan view of the die assembly and locking mechanism and is taken along the line 3—3 of FIG. 1.

FIG. 4 is an enlarged fragmentary cross-section taken substantially along the line 4—4 of FIG. 3.

FIG. 5 is an exploded perspective view of the locking mechanism.

FIG. 6 is a fragmentary exploded perspective view of the die assembly.

DETAILED DESCRIPTION OF THE PREFERRED EMBODIMENT

As shown in the drawings for purposes of illustration, the invention is embodied in a punch press in which a punch 11 is reciprocated upwardly and downwardly and coacts with an underlying die 13 to form a hole in an intervening workpiece (not shown) during each downstroke of the punch. Surrounding the punch is a cylindrical stripper housing 14 whose lower end carries an apertured stripper plate 15 which overlies the upper surface of the workpiece.

During the punching operation, the stripper plate 15 always remains in a fixed position and engages the workpiece on the upstroke of the punch 11 thereby to strip the workpiece from the punch as the punch is retracted. In this particular instance, the minimum vertical clearance between the stripper plate and the die is approximately one-eighth inch, and, to accommodate workpieces of greater thicknesses, the stripper housing 14 and plate 15 may be adjusted upwardly through a distance as much as five-eighths inch in essentially the same manner as disclosed in Scott U.S. application Ser. No. 168,099, now U.S. Pat. No. 3,720,125 filed Aug. 2, 1971 and assigned to the assignee of the present invention.

The die 13 forms one main part of a die assembly 16 whose other main part is formed by a die adapter 17 which is usually matched to the die and is sized and shaped to fit snugly but removably in a die shoe 19. The latter is anchored by screws 20 (FIG. 3) to a flat bolster plate 21 (FIG. 1) which, in turn, is anchored rigidly to the bed 23 or main support of the press. Slugs punched from the workpiece are removed from the die through a vertically extending slug chute 24 extending through the die adapter, the die shoe and the bolster plate.

More specifically, the upper end of the die shoe 19 is formed with a generally circular and upwardly opening recess in the form of a counterbore 25 whose side and bottom walls are precisely finished and define a seat into which the die adapter 17 is removably telescoped and accurately located. A generally similar counterbore 26 is formed in the die adapter 17 and receives and accurately locates the die 13. To prevent the adapter 17 from turning relative to the shoe 19, an upwardly opening and radially extending keyway 27 is formed through the rear side wall of the counterbore 25 and slidably but snugly receives a rigid key 29 projecting outwardly from the rear of the adapter. A cylindrical key 30 extends slidably through the front wall of the counterbore 26 in the adapter and seats at its inner end in a downwardly and forwardly inclined notch 31 formed in the front of the die. A coiled compression spring 33 (FIG. 1) is telescoped into a hole 34 drilled in the upper side of the adapter and fits into a flat-bottomed notch 35 on the underside of the key 30 to permit radial sliding of the latter through a limited distance out of the notch 31 while retaining the key in the adapter.

In accordance with the present invention, provision is made of a novel locking mechanism 37 for clamping the die assembly 16 tightly within the shoe 19 but capable of permitting removal of the assembly from the shoe in a substantially horizontal direction to that such removal can be effected quickly and easily in spite of the obstruction presented by the overlying stripper housing 14 without need of moving the housing to increase the vertical clearance above the die assembly.

For these purposes, the locking mechanism includes a locking arm 39 which clamps the die assembly when disposed in a locked position shown in FIG. 1 and which, upon being moved to a released position shown in FIG. 2, is disposed below the bottom 40 of a radially extending slot 41 in the counterbore 25 of the die shoe 19 so as to permit horizontal removal of the die assembly through the slot and across the arm. Thus, the die assembly can be removed quickly and easily from the shoe in spite of the limited vertical clearance between the die 13 and the stripper housing 14 and, by the same token, a different die assembly can be easily loaded into the shoe.

More particularly, the slot 41 in the die shoe 19 opens upwardly and extends radially through the front wall of the counterbore 25, has a width just slightly greater than the diameter of the counterbore, and preferably is formed with a depth which is somewhat less than the depth of the counterbore. The difference between the depth of the slot 41 and the depth of the counterbore 25 is just slightly less than the minimum vertical clearance between the die 13 and the stripper housing 14 and, in this particular instance, is thus just slightly less than one-eighth inch. As a result of the depth of the slot, a short vertical portion 43 (FIG. 2) of the front wall of the counterbore 25 is left intact around and below the slot to pilot and locate the die adapter 17 and yet the adapter can be lifted vertically to the level of the bottom 40 of the slot and then moved horizontally through the slot and out of the shoe 19.

The locking arm 39 is located forwardly of and is centered relative to the slot 41 (see FIGS. 1 and 3) and is formed by an upper nose 45 (FIG. 5) which extends across and is joined to a pair of horizontally spaced and vertically extending plates 46. The latter straddle an upstanding support block 47 fitted in a hole 49 (FIG. 1) in the bolster plate 21 and bolted to a mounting strip 50 secured to the underside of the bolster plate. A sheet metal housing 51 secured to the bolster plate encloses the support block 47 and includes a top wall formed with an upwardly opening slot 53 through which the locking arm projects when the latter is in its locked position shown in FIG. 1. The nose 45 of the locking arm is retracted into the housing and is spaced below the top of the housing when the locking arm is in its released position shown in FIG. 2.

As shown in FIGS. 1 and 5, a horizontal pivot pin 55 is located forwardly of and below the slot 41 and extends through the plates 46 and the support block 47 to mount the locking arm 39 for swinging between its locked and released positions. To swing the arm between such positions, a pneumatic cylinder 56 (FIG. 1) is supported on the underside of the mounting strip 50 and includes a vertically reciprocable rod 57 which extends upwardly through a vertical hole 59 (FIG. 5) in the support block 47. A horizontal pin 60 is carried on the upper end portion of the rod and extends snugly but slidably through a vertical slot 61 in the block and through inclined slots 63 formed in the plates 46, the slots 63 extending across the slot 61 and extending substantially horizontally when the arm is disposed in its released position shown in FIG. 2.

When the rod 57 is extended upwardly by actuating the cylinder 56, the pin 60 rides upwardly in the vertical slot 61 and cams against the upper edges of the slots 63 to swing the locking arm 39 upwardly about the pin

55 toward the locked position shown in FIG. 1. As the arm approaches the locked position, the nose 45 engages the outer end of the key 30 and forces the latter inwardly against the bottom of the notch 31. The free end 65 of the nose is inclined downwardly and forwardly and thus the nose exerts a downwardly and rearwardly directed force on the key. Such force acts through the die 13 to crowd and clamp the die adapter 17 downwardly and rearwardly against the bottom and rear walls of the counterbore 25 and, at the same time, acts on the die to crowd and clamp the latter downwardly and rearwardly against the bottom and rear walls of the counterbore 26.

When the locking arm 39 is in its locked position, the slots 63 in the arm are inclined upwardly and outwardly relative to the rod 57 at an angle of about 10° and, as a result, the force exerted on the rear edge of the slots by the pin 60 includes a horizontal component of relatively large magnitude for passing the nose 45 against the key 30. Also, the reaction force on the locking arm is transmitted by the pin 60 to the edges of the vertical slot 61 in the support block 49 and thus such force is ultimately resisted by the bed 23 of the press rather than imposing bending stresses on the rod 57 of the cylinder 56. Accordingly, the unique arrangement of the slots 61 and 63 enables effective actuation of the arm 39 with the vertically movable pin 60 and also avoids the exertion of bending stresses on the rod 57 and the cylinder 56.

During the punching operation, the die 13 is anchored rigidly within the die adapter 17 and the latter is clamped tightly to the die shoe 19 by the locking arm 39. When the tooling is to be changed, the adapter is unclamped from the shoe and both the adapter and the die (i.e., the die assembly 16) are removed from the shoe as a unit and replaced with a different die assembly.

To remove the die assembly 16 from the shoe 19, the rod 57 is shifted downwardly to swing the locking arm 39 downwardly to the released position shown in FIG. 2. In this position, the entire arm is disposed below the horizontal plane containing the bottom 40 of the slot 41 in the shoe. Accordingly, the die assembly may be removed from the shoe by first lifting the assembly vertically a slight distance to clear the short portion 43 of the front wall of the counterbore 25 and then by moving the assembly forwardly and horizontally beneath the stripper housing 14, through the slot 41 and across the retracted locking arm 39 (see FIG. 2). A new assembly may be inserted into the shoe by following the same steps in reverse order and thus changing of the die assemblies may be effected quickly and easily in spite of the obstruction presented by the overhanging stripper housing 14.

From the foregoing, it will be apparent that the present invention brings to the art a new and improved mechanism 37 for effectively locking the die assembly 16 to the die shoe 19 while permitting the assembly to be moved horizontally between the shoe and the stripper housing 14 when inserted into or removed from the shoe. As a result of actuating the clamping arm 39 with the pin 60 movable vertically in the slots 61 and 63, the mechanism 37 is of comparatively simple and compact construction and yet is relatively durable and trouble-free during service use.

I claim as my invention:

1. A punch press having a support, a die shoe attached to said support and formed with an upwardly opening recess defining a seat, and a die assembly telescoped removably into said seat and projecting upwardly from said shoe, the improvement in said press comprising, an upwardly opening and radially extending slot formed through one wall of said recess and having a width at least equal to the diameter of the recess, a locking arm, and means mounting said arm on said support for upward and downward movement between:

- a. a locked position in which the arm extends upwardly alongside said slot and engages the die assembly to clamp the latter to said die shoe, and
- b. a released position in which the arm is disengaged from said die assembly and is spaced below the upper end of said slot to permit removal of the die assembly from the recess in the shoe by moving the assembly generally horizontally out of said slot and across said arm.

2. A punch press having a support, a die shoe attached to said support and formed with an upwardly opening counterbore, and a die assembly telescoped removably into said counterbore and projecting upwardly from said shoe, the improvement in said press comprising, an upwardly opening and radially extending slot formed through one wall of said counterbore and having a width at least equal to the diameter of the counterbore, a locking arm mounted on said support to swing upwardly and downwardly about a generally horizontal axis located outwardly of and below said slot, and means connected to said arm for swinging the latter upwardly and downwardly about said axis between:

- a. a locked position in which the arm engages the die assembly and clamps the latter to said die shoe, and
- b. a released position in which the arm is disengaged from said die assembly and is spaced below the bottom of said slot to permit removal of the die assembly from the shoe by moving the assembly generally horizontally across the bottom of the slot and across said arm.

3. A punch press as defined in claim 2 in which the depth of said slot is slightly less than the depth of the counterbore whereby the entire periphery of said die assembly is seated in said counterbore but said assembly may be removed from said shoe by lifting the assembly to the level of the bottom of the slot and then moving the assembly generally horizontally across the bottom of the slot.

4. A punch press as defined in claim 2 further including an elongated and generally vertical slot formed in said support and spaced from said axis, an elongated slot formed through said locking arm and crossing said vertical slot, said means comprising a pin slidably mounted within said elongated slots, and mechanism for reciprocating said pin upwardly and downwardly within said vertical slot.

5. A punch press as defined in claim 4 in which said slot in said locking arm is located so as to slant upwardly and outwardly when said arm is in said locked position.

6. A punch press as defined in claim 5 in which said slot in said locking arm is located so as to extend generally horizontally when said arm is in said released position.

7. A punch press having a support, a die shoe attached to said support and formed with a first upwardly opening counterbore, a die adapter telescoped removably into said first counterbore and formed with a second upwardly opening counterbore, a die telescoped removably into said second counterbore, and a radially extending key mounted slidably in the side wall of said second counterbore and having an inner end engageable with the outer side of said die, the improvement in said press comprising, an upwardly opening and radially extending slot formed through one wall of said first counterbore and having a width at least equal to the diameter of such counterbore, a locking arm mounted on said support to swing about a generally horizontal axis located outwardly of and below said slot, an elongated vertical slot formed in said support and located outwardly of said axis, an elongated slot formed through said locking arm and crossing said vertical slot, a pin slidably mounted within said elongated slots, and means for reciprocating said pin vertically to swing said locking arm upwardly and downwardly about said axis between:

- a. a locked position in which the free end of the arm presses against the outer end of said key to clamp said die into said second counterbore and to clamp said die adapter into said first counterbore, and
- b. a released position in which the arm is disengaged from said key and is spaced below the upper surface of said die shoe to permit removal of the die adapter from the shoe by moving the adapter generally horizontally across the bottom of said radially extending slot and across said arm.

8. A punch press as defined in claim 7 in which the depth of said radially extending slot is slightly less than the depth of said first counterbore whereby the entire periphery of said die adapter is seated in said first counterbore but said adapter may be removed from said shoe by lifting the adapter to the level of the bottom of said radially extending slot and then moving the adapter generally horizontally across the bottom of said radially extending slot.

9. A punch press as defined in claim 7 in which the free end of said arm is inclined downwardly and outwardly when said arm is in said locked position and acts through said key to force said die radially and downwardly against the side and bottom walls, respectively, of said second counterbore and to force said die adapter radially and downwardly against the side and bottom walls, respectively, of said first counterbore.

10. A punch press as defined in claim 7 in which said slot in said locking arm is located so as to slant upwardly and outwardly when said arm is in said locked position.

11. A punch press as defined in claim 10 in which said slot in said locking arm is located so as to extend generally horizontally when said arm is in said released position.
